(57) **CLAIM**

The ornamental design for a carrier beam extrusion as shown.

DESCRIPTION

FIG. 1 is a front elevational view of a carrier beam extrusion showing my new design;

FIG. 2 is a rear elevational view of the carrier beam extrusion;

FIG. 3 is a right side elevational view of the carrier beam extrusion;

FIG. 4 is a left side elevational view of the carrier beam extrusion;

FIG. 5 is a top plan view of the carrier beam extrusion; and, FIG. 6 is a bottom plan view of the carrier beam extrusion. The carrier beam extrusion is shown with a symbolic break in its length. Any portion between the symbolic break, including the broken line break lines, forms no part of the claimed design.
